SHEET LIFTER

Erard J. Shaughnessy, Chicago, Ill., assignor to
Cullen-Friestadt Company, Chicago, Ill., a corporation of Illinois

Application May 13, 1938, Serial No. 207,682

11 Claims. (Cl. 294—117)

The present invention relates generally to lifters for handling stacks of metallic sheets or like articles. More particularly the invention relates to that type of sheet lifter which is adapted to be hoisted and moved from place to place by a crane or overhead hoist and as the main or principal parts thereof comprises the following: an elongated supporting element which is adapted normally to extend horizontally and has an upstanding loop on the central portion thereof whereby it may be attached to a hook or other connecting device on the operating end of the crane or hoist with which the lifter is used; a pair of opposed horizontally elongated complementary jaws which are shiftable to and from one another into and out of engagement with the side margins of the sheets and consist of upper members which are pivotally connected to and depend from the supporting element and lower members which depend from the lower ends of the upper members and are provided at the bottom portions thereof with inwardly extending means for underlying and supporting the side margins of the sheets; and gear mechanism which is associated with, and carried by, the supporting element and operates in response to actuation thereof conjointly to shift the jaws to or from one another.

One object of the invention is to provide a lifter of this type which is an improvement upon, and has certain advantages over, previously designed lifters of the same general character and in addition has greater capabilities of use and is more efficient in operation.

Another object of the invention is to provide a sheet lifter of the type and character under consideration in which the lower members of the jaws are pivotally connected at the upper ends thereof to the lower ends of the upper members so that they may be angularly adjusted with respect to said upper members and thus properly adapted or adjusted for use in connection with stacks of sheets which vary in width, and in addition have associated with the upper ends thereof simple and novel means whereby they may be locked or fixed in their various adjusted positions.

Another object of the invention is to provide a sheet lifter of the last mentioned character in which the means for locking or fixing the lower members of the jaws in their various angular positions with respect to the upper members of the jaws comprises notched sector-shaped elements at the upper ends of the lower jaw members and horizontally extending longitudinally slidable notched bars which are carried by the

upper jaw members and are adapted when slid or shifted in one direction to have the notches thereof register with the sector-like elements and thus permit the lower jaw members to swing laterally for adjustment purposes and when shifted in the opposite direction to interlock with the adjacent notches of said elements and thus lock the lower jaw members in place, that is, in fixed relation with the upper jaw members.

A further object of the invention is to provide a sheet lifter of the hereinbefore specified type which includes means whereby when the lifter is placed on the ground or the subjacent floor in connection with non-use or storage thereof the gear mechanism is automatically locked against actuation and the jaws are thus precluded from spreading or swinging apart in response to the weight of the supporting element and gear mechanism and injuring or damaging any person or object in the immediate vicinity of the lifter.

A still further object of the invention is to provide a sheet lifter which is generally of new and improved construction and not only may be manufactured at a low and reasonable cost but also effectively and efficiently fulfills its intended purpose.

Other objects of the invention and the various advantages and characteristics of the present lifter will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a side elevation of a sheet lifter embodying the invention, parts being broken away and shown in section in order to illustrate in detail the construction and design of the mechanism for automatically locking the gear mechanism against actuation when the lifter is dropped or placed on the subjacent ground or floor in connection with disengagement of the crane or hoist hook from the loop on the central portion of the elongated supporting element;

Figure 2 is a transverse sectional view taken on the line 2—2 of Figure 1 and further illustrating the construction and arrangement of the mechanism for locking the jaws against separation or spreading when the lifter is not in use;

Figure 3 is a fragmentary perspective view showing the arrangement and design of the front

end of the longitudinally slidable notched bar of the locking means for one of the jaws, and illustrating in detail the arrangement and construction of the releasable latch which is associated therewith and serves releasably to hold such bar against longitudinal shift or sliding movement;

Figure 4 is a vertical longitudinal sectional view of the parts which are illustrated in Figure 3;

10 Figure 5 is a vertical transverse sectional view of the lifter taken on line 5—5 of Figure 1 and showing the jaws swung together and the lower jaw members adjusted or set for handling narrow or small sheets; and

15 Figure 6 is a vertical transverse sectional view showing the jaws of the lifter swung apart and the lower jaw members set or adjusted with respect to the upper jaw members so that they are capable of handling comparatively wide sheets.

20 The lifter which is shown in the drawings constitutes the preferred embodiment of the invention. It is adapted in connection with a crane or overhead hoist having a hook at its operating end to lift or move from one place to another a 25 stack of metallic sheets or like articles, and comprises an elongated supporting element 7, a pair of opposed horizontally elongated complementary jaws 8 and 9, and gear mechanism 10 for conjointly shifting the jaws to and from one another.

30 The supporting element 7 is adapted normally to extend horizontally. It carries the jaws 8 and 9 and the gear mechanism 10 and is in the form of an I-beam. As shown in the drawings, the supporting element carries the jaws in a depending manner and comprises a vertical web 11, a horizontally extending top flange 12, and a horizontally extending bottom flange 13. On its central portion the element 7 has an upstanding loop 14 for the hook at the operating end of the crane 40 or hoist with which the lifter is used. This loop embodies a pair of depending legs 15, the lower ends of which extend through holes in the top flange 12 of the element 7 and are arranged in straddled relation with the web 11 of the element 45 and so that the bottom faces or extremities thereof rest upon the bottom flange 13. The portions of the legs 15 which are disposed between the top and bottom flanges of the supporting element, that is, the lower ends of the legs 50 are welded or otherwise fixedly secured to the web 11 so that the hook is permanently attached or connected to the element 7.

The opposed horizontally elongated complementary jaws 8 and 9 are adapted, as hereinafter 55 described, to be shifted to and from one another in response to actuation or operation of the gear mechanism 10. They extend lengthwise of the supporting element 7 and comprise upper members 16, lower members 17, and horizontally extending angle iron bars 18. The upper members 60 16 have inturned or inwardly extending upper ends and each comprises a pair of laterally spaced plate metal pieces 19. The upper ends of the upper members 16 of the jaws are pivotally 65 connected by way of pivot pins 20 to laterally extending pivot lugs 21 on the supporting element 7. Preferably the upper members of the jaw 8 are transversely aligned with the upper members of the jaw 9. The pivot lugs 21 fit between and are welded to the top and bottom flanges of the element 7 and project into the spaces between the upper ends of the pairs of pieces 19 which form or constitute the upper jaw members 16. The pins 20 extend through aligned holes in the pivot lugs and the upper ends of the

pieces 19 and together with the lugs so pivotally support the jaws 8 and 9 that the latter are free to swing to and from one another into and out of a gripping relation with a stack of sheets. The lower members 17 of the jaws extend substantially vertically and carry at their lower ends the horizontally extending angle bars 18. The upper ends of the members 17 project into the spaces between the lower ends of the pairs of pieces 19 and are pivotally supported by pins 22 in such a manner that the lower jaw members may be swung in different angular positions with respect to the upper members in order to adapt the lifter for use in connection with stacks of wide sheets as well as small sheets. The pins 22 project through aligned holes in the upper ends of the jaw members 17 and the lower extremities of the pieces 19 and are suitably retained against axial displacement. The angle iron bars 18 consist of substantially vertical legs 23 and substantially horizontal legs 24. The vertical legs are welded or otherwise fixedly secured to the inner faces of the lower ends of the lower jaw members 17 and are adapted when the jaws are shifted towards one another, as hereinafter described, into 25 hoisting relation with a stack of sheets, to abut against the side edges of the lowermost sheets. The horizontal legs 24 are formed integrally with, and project inwardly from, the bottom margins of the legs 23 and are adapted to underlie the side margins of the sheets, as shown in Figure 6. The upper ends of the lower jaw members 17 are provided with integral sector shaped elements 25, as shown in Figures 5 and 6. These elements are positioned above the pivot 30 pins 22 and fit within the spaces between the lower ends of the pairs of pieces 19. They have arcuate series of notches 26 in the top portions thereof and coat with a pair of horizontally extending bars 27 to form means for holding the lower members 17 of the jaws 8 and 9 in their various adjusted positions with respect to the upper members 16. The bars 27 are associated with the two jaws, respectively, and are positioned above the pivot pins 22 and directly over the 35 sector-shaped elements 25. They are mounted for longitudinal sliding movement in slots 28 in the central portions of the pieces 19 which form the upper jaw members 16 and have notches 29 in the bottom portions thereof. Said notches 29 are normally located behind the elements 25 and are adapted when the bars 27 are shifted forward, that is, towards the front of the lifter (right hand end of lifter as viewed in Figure 1) 40 to be brought into registry with the top portions of the elements 25 and release such elements as far as the bars are concerned so that the lower members 17 of the jaws are free to be 45 swung laterally into different angular positions relatively to the upper members 16 of the jaws. The portions of the bars 27 which are directly in front of the slots 28 constitute locking dogs 30. The latter are adapted when the locking bars 27 are slid rearwards after proper adjustment of the lower members 17 with respect to the upper members 16 to fit within the adjacent notches 26 of the sector shaped elements 25 and thus to lock said elements and the lower members 17 of the jaws in fixed or set relation with respect to the upper members 16. As a result of the arrangement 50 and location of the notches 29 and the dogs 30 the lower members 17 of the jaws may be released for angular adjustment with the upper members merely by shifting the bars 27 forwards and locked in their adjusted position by shifting 55

the bars 27 rearwards. The elements 25 are of such size and have a sufficient number of notches 26 that said lower members 17 are capable of being properly adjusted to adapt the lifter for use in connection with sheets of all sizes within the range of swinging movement of the two jaws 8 and 9. Longitudinal shift or sliding movement of the two bars 27 is effected by means of a pair of levers 31. These levers, as shown in Figures 3 and 4, are located at the front end of the lifter and are disposed adjacent to, and in parallel relation with, the lower ends of the upper members 16 at the front end of the supporting element 7. The lower ends of the levers are bifurcated. They are arranged in straddled relation with the front ends of the bars 27 and are pivotally connected by pins 32 at their bottom or lower extremities to lugs 33. Such lugs are welded or otherwise fixedly connected to the lower ends of the front most pieces 19 and carry the pins 32 in such manner that the levers 31 are adapted to swing back and forth longitudinally of the lifter. The upper ends of the levers are bent forwardly and then upwards and form handles 34. The portions of the levers which straddle the front ends of the bars 27 have vertically extending slots 35 through which extend transversely extending pins 36. The pins serve to connect the bars to the levers so that the bars are shifted forwardly in response to forward swing of the levers and rearwards in response to rearward swing of such levers. The slots 35 are vertically elongated so as to permit of relatively vertical movement of the pins and the adjacent portions of the levers during swinging of the latter. The rear ends of the bars are provided with enlargements or heads 37 which serve to limit forward movement of the bars. These heads are adapted when the bars are shifted forwardly so as to bring the slots 29 into registry with the sector shaped elements 25 to abut against the rearmost pieces 19 and prevent or preclude further forward movement of the bars. In order to lock the bars against accidental or undesired displacement when they are in their locked position, that is, when the dogs 30 are in interlocked relation with the adjacent notches 26 in the elements 25 vertically slidably latches 38 are provided. These latches are disposed directly above the front ends of the bars 27 and are associated with a pair of brackets 39. The latter are welded to the lower ends of the inner or rear pieces 19 of the front most upper jaw members 16 and have vertically spaced horizontally extending head equipped pins 40 which extend through slots 41 in the latches 38 and form suitable mountings whereby the latches are permitted to slide vertically. The lower ends of the latches are shaped to form teeth 42 and these teeth are adapted when the bars 27 are shifted rearwards into their locking position to fit within V-shaped cut-outs 43 in the top portions of the front ends of the bars. Compression springs 44 are applied to laterally extending lugs 45 on the upper ends of the latches in such manner that they serve to urge the latches downwards and thus hold the teeth 42 in the cut-outs 43 when the cut-outs are disposed beneath the latches. As shown in Figure 3, the lugs 45 are extended so as to form handles whereby the latches may be gripped and raised in connection with the release of the bars 27. The springs 44 surround a pair of rods 46 which are carried by and extend upwardly from the lugs 45. The upper ends of the rods extend through holes in a pair of lugs 48 which are spaced above the brackets 39, and as shown in Figure 4, are welded to the rearmost pieces 19 of the upper members 16 at the front of the lifter. At their rear ends the lugs 48 are provided with a pair of laterally extending fingers 49. As shown in Figure 3, these fingers overlie the laterally extending lugs 45, and are adapted to be gripped in connection with lift or raising of the latches. When it is desired to adjust the lower members 17 of the jaws relatively to the upper members, the latches 38 are first released by raising them a sufficient distance to disengage the teeth 42 from the cut-outs 43 in the bars. After proper or sufficient raising of the latches the levers 31 are swung forwardly until they are arrested as the result of abutment of the heads 37 against the adjacent jaw member pieces 19. Such swinging effects sufficient forward movement or shift of the bars 27 to bring the notches 29 in registry with the notches 26 in the top portions of the sector shaped element 25, and thus, as hereinbefore described, frees the lower jaw members 17 so that they may be swung laterally with respect to the upper jaw members. After proper adjustment or swinging of the lower jaw members the levers 31 are swung rearwards in order to bring the dogs 30 into interlocked relation with the adjacent or contiguous notches 26. As soon as the bars 27 reach the end of their inward stroke, the latches 38, in response to the action of the compression springs 44, snap into the cut-outs 43 and thus lock the bars in place. The rear side corners of the dogs 30 are preferably beveled, as shown in Figure 3, so that they can enter readily the adjacent notches 26 in connection with rearward shift of the bars 27. The bars 27 constitute or exemplify means whereby the lower arms of each jaw may be conjointly released and then locked in connection with angular adjustment thereof with respect to the upper jaw members.

The gear mechanism 10 for conjointly shifting the jaws 8 and 9 to and from one another comprises a hand wheel 50, a horizontal shaft 51, a shaft 52, a gear unit 53, a pinion 54, an internal gear segment 55, a shaft 56, and sets of arms 57 and 58. The shaft 51 extends longitudinally of the lifter and is located in front of and a slight distance beneath the elongated supporting element 7. It is journaled in an outer bearing bracket 59 and an inner bearing bracket 60 and has the hand wheel 50 keyed or otherwise fixedly secured to the front end thereof. As shown in Figure 1, the bracket 59 is connected to and extends forwardly from the front or forward end of the element 7 and, as shown in Figure 5, the bracket 60 is connected to and extends downwardly from the front portion of the bottom flange 13 of the element. The shaft 52 is disposed directly beneath the front end of the supporting element 7 and has the front end thereof connected by a universal joint 61 to the rear end of the shaft 51. The gear unit 53 is connected by a suitable bracket to, and underlies the central portion of the element 7, and embodies a drive shaft 62 and a driven shaft 63. The drive shaft is connected to the rear end of the shaft 52 by a universal joint 64 and operates through the medium of the unit gearing to drive the driven shaft 63. The latter is disposed under the rear end of the element 7 and extends horizontally. It is journaled in a bearing bracket 65 and carries the pinion 54 at its rear end. The bracket 65 is secured to, and depends from, the rear portion of the bottom flange 13 of the element 7. The shaft 56 extends horizontally and

is disposed beneath the supporting element 7. The front end of the shaft 56 is journaled in the lower end of the bearing bracket 59 and the rear end of said shaft is journaled in the lower end or portion of the bearing bracket 55 and carries the internal gear segment 55. The latter meshes with and is driven by the pinion 54 and is keyed to the shaft 56 so that the latter is caused to rock or rotate in response to swinging of the 5 segment. When the hand wheel 59 is rotated or turned in one direction, the shafts 51 and 52, the gear unit 53, the pinion 54, and the internal gear segment 55 operates to rock or turn the shaft 56 in one direction, and when the hand wheel 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500

In addition to the supporting element 7, the jaws 8 and 9 and the gear mechanism 10, the lifter comprises means for automatically locking the gear mechanism against actuation or rotation when the lifter is placed on the ground or the subjacent floor in connection with disengagement of the crane or hoist hook from the loop 14 on the central portion of the element 7. Such means is associated with the loop and comprises a pair of substantially horizontal bars 70, a vertically extending link 71, a horizontally extending lever 72, and a dog 73. The bars 70 straddle the upper or curved portion of the loop and are pivotally connected at the front ends thereof to a lug 74 so that they are free to swing vertically. The rear ends of the bars straddle the upper end of the link 71 and are connected to the latter by a pivot pin 75. The lower end of the link 71 extends through a hole in the top flange 12 of the supporting element 7 and is disposed adjacent to one face of the web 11 of the element. The lever 72 is disposed adjacent to, and extends parallel to, said one face of the web 11 and is pivotally connected at the rear end thereof so that it is free to swing vertically. The front end of the lever 72 is connected by a pivot pin 76 to the lower end of the link 71 with the result that the lever 72 is caused to swing upwards in response to upward swinging of the bars 70. The dog 73 is pivotally connected to, and depends from, the central portion of the lever 72 and is adapted when the lever 72 is shifted or swung downwards to coact with a set or series of external ratchet teeth 77 on the gear segment 55 and to lock such segment together with the other parts of the gear mechanism 10 against actuation or rotation in one direction. The bars 70 are so disposed with respect to the upper or curved portion of the loop that when the crane or hoist hook

is inserted into the loop and then raised in connection with hoisting of the lifter they are raised as shown in dotted lines in Figure 1. In response to raising of the bars 70 the lever 72 swings upwards and operates to disengage the dog 73 from the ratchet teeth 77. As soon as the dog is free from the ratchet teeth the gear segment 55 is released so that the gear mechanism 10 is operative to swing the jaws 8 and 9 to and from one another. When the lifter is lowered onto the subjacent ground or floor in connection with non-use or storage thereof, the bars 70 swing downwards as soon as the crane or hoist hook becomes disengaged from the loop 14. As soon as the bars 70 swing or drop downwards the lever 72, in turn, swings downwards and causes the dog 73 to slide or move into interlocked relation with the ratchet teeth 77. The dog 73 extends downwardly through, and is slidably mounted in, a hole in the bottom flange 13 of the 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500

The operation of the lifter is as follows: When it is desired to hoist or move a stack of comparatively narrow sheets the lower members 17 of the jaws before lowering the lifter into straddled relation with the sheets are so angularly adjusted with respect to the upper jaw member 16 that when the jaws are swung towards one another into engagement with the side margins of the sheets the legs 24 of the angle iron bars 21 are substantially horizontally disposed. In connection with adjustment of the lower jaw member 17 the levers 31 by manipulation of the handles 34 are swung outwards until arrested by the heads 37 striking against the rearmost pieces 19 of the upper jaw members 16 at the rear end of the lifter. As soon as the bars 21 are shifted forwards by manipulation of the levers and the lower members 17 of the jaws are thus freed such members are swung into the proper angular position with respect to the upper members. Thereafter the levers 31 are swung inwards in order to effect locking of the lower jaw members by way of the dogs 38 and the notch equipped sector-shaped elements 25. As soon as the levers 31 are shifted rearwards sufficiently to bring the bars 21 into their full locking position, the latches 38 snap downwards as hereinbefore described into a position wherein the teeth 42 interlock with the cut-outs 43 in the upper portions of the bars 21. After proper adjustment of the lower members 17 of the jaws the lifter is lowered so as to bring the jaws into straddled relation with the side margins of the sheets. Thereafter the hand wheel 50 is turned so as to cause the jaws to swing inwardly into a position wherein the vertical legs 23 of the angle iron bars abut against the side edges of the lowermost sheets of the stack and the horizontal legs 24 of the bars underlie the side margins of the bottom sheet of the stack. After such manipulation of the hand wheel 50 the lifter together with the stack of sheets is lifted and then moved to the desired location or place by manipulation of the crane or overhead hoist with which the lifter is associated. As soon 75

as the proper location or space is reached the lifter is lowered and the hand wheel 50 is reversely rotated so as to swing apart the jaws 8 and 9. In the event that it is desired to use the 5 lifter in connection with a stack of comparatively wide sheets the lower members 17 of the jaws are released from the upper members by outward pull of the levers 31 and are swung inwardly to the proper extent. Thereafter the levers are 10 shifted rearwards in order to lock the lower members of the jaws in fixed or set relation with the upper members. Immediately prior to outward or forward swing of the levers 31 the latches 38 are released by gripping the lugs 45 and then 15 raising them against the force of the compression springs 44. When it is desired to store the lifter it is swung or shifted to the place of storage and then lowered onto the subjacent ground or floor. As soon as the hook of the crane or 20 hoist is out of engagement with the U-shaped upper portion of the loop 14 the bars 70 swing downwards and through the medium of the link 71 and the lever 72 cause the dog 73 to drop 25 into engagement with the ratchet teeth 77 and effect such locking of the gear mechanism 10 that the jaws 8 and 9 of the lifter cannot swing or spread outwards as the result of the application of weight thereto. When it is again desired to use the lifter the hook of the crane or hoist 30 is manipulated in hooked relation with the loop 14 and then the lifter is raised. As soon as the hook comes into engagement with and operates to raise the bars 70 the dog 73 is automatically raised out of engagement with the ratchet teeth 35 74 and the gear mechanism 10 is thus freed or unlocked so that it is capable of being manipulated by the hand wheel 50 in connection with opening and closing of the jaws.

The herein described sheet lifter is extremely 40 efficient in operation. In addition it has a wide range of use in that it is possible to adjust the lower jaw members relatively to the upper members and thus adapt the lifter for use in connection with narrow sheets as well as wide sheets. 45 The lifter is safe as far as operation is concerned because due to the automatic locking means for the gear mechanism 10 there is no likelihood of the jaws 8 and 9 swinging apart and injuring or damaging any person or object in the immediate vicinity of the lifter when the latter 50 is dropped or lowered onto the subjacent ground or floor.

Whereas the lifter has been described as embodying a hand wheel for operating the gear mechanism 10, it is to be understood that any 55 other drive means for the mechanism may be employed such, for example, as a chain driven wheel (see Figure 1) or an electric motor. It is also to be understood that each jaw may include more 60 than two upper and lower members and that the invention is not to be restricted to the specific details set forth since they may be modified within the scope of the appended claims without departing from the spirit and scope of the invention. 65

Having thus described the invention, what I claim as new and desire to secure by Letters Patent is:

1. A lifter adapted for use in handling sheets 70 and like articles and comprising a pair of oppositely facing complementary jaws mounted to move to and from one another and embodying a plurality of upper members and in addition a plurality of depending lower members having 75 means at the lower ends thereof for gripping the

sheets and connected pivotally at the upper ends to the upper members so that they may be swung laterally relatively to the latter into different angular positions in order to adjust the jaws for use with narrow or wide sheets; means operable 5 conjointly to lock the lower members of one jaw in their various adjusted positions with respect to the upper members of said one jaw and also conjointly to release such lower members for adjusting purposes, including an elongated horizontal element extending longitudinally and substantially throughout the full length of said one jaw; means operable conjointly to lock the lower members of the other jaw in their various adjusted positions with respect to the upper 10 members of said other jaw and also conjointly to release such lower members for adjusting purposes, including a corresponding elongated horizontal element extending longitudinally and substantially throughout the full length of said other jaw; and means for conjointly shifting the jaws 15 to and from one another.

2. A lifter adapted for use in handling sheets and like articles and comprising a pair of oppositely facing complementary jaws mounted to move to and from one another and embodying upper members and in addition aligned depending lower members having sheet gripping means at the lower ends thereof and connected pivotally at their upper ends to the upper members so that they may be swung laterally relatively to the latter into different angular positions in order to adjust the jaws for use with narrow or wide sheets, means for releasably locking the lower members of the jaws in their various adjusted positions with respect to said upper members including notched elements at the upper ends of the lower members and dog equipped bars extending longitudinally of the jaws and carried by the upper members so that they are 40 longitudinally shiftable to bring the dogs thereof into interlocked relation with the notches of the said elements, and means for conjointly shifting the jaws to and from one another. 35

3. A lifter adapted for use in handling sheets 45 and like articles and comprising a pair of oppositely facing complementary jaws mounted to move to and from one another and embodying upper members and in addition aligned depending lower members having means at the lower 50 ends thereof for gripping the side margins of the sheets and connected pivotally at their upper ends to the upper members so that they may be swung laterally relatively to the latter into different angular positions in order to adjust the 55 jaws for use with narrow or wide sheets, means for releasably locking the lower members of the jaws in their various adjusted positions with respect to said upper members including notched elements at the upper ends of the lower members, 60 dog equipped bars extending longitudinally of the jaws and carried by the upper members so that they are longitudinally shiftable into and out of an operative position wherein the dogs thereof are interlocked with certain of the notches 65 of said elements and latches for holding the bars in their operative position, and means for conjointly shifting the jaws to and from one another.

4. A lifter adapted for use in handling sheets 70 and like articles and comprising a pair of oppositely facing horizontally elongated complementary jaws pivotally suspended to swing to and from one another and embodying upper members and in addition aligned depending lower 75

members having inwardly extending means at the lower ends thereof for underlying the side margins of the sheets and connected pivotally at their upper ends to the members so that they 5 may be swung laterally relatively to the latter into different angular positions in order to adjust the jaws for use in connection with narrow or wide sheets, means for releasably locking the lower members of the jaws in their various adjusted 10 positions with respect to said upper members including sector-like elements connected fixedly to and extending upwardly from the upper ends of the lower members and having series of notches in the top portions thereof, dog 15 equipped bars extending longitudinally of the jaws and carried by the upper jaw members so that they are longitudinally slidable into and out of an operative position wherein the dogs thereof are interlocked with certain of the 20 notches and handle equipped levers pivotally attached to certain of the upper jaw members and connected to the bars so as to shift the latter longitudinally in response to swinging movement 25 thereof, and means for conjointly swinging the jaws to and from one another.

5. A lifter adapted for use in handling sheets and like articles and comprising in combination a horizontal supporting element having an up-standing loop for attachment to the hook of a 30 crane or over head hoist, a pair of oppositely facing complementary jaws connected to the element so that they depend therefrom and are movable to and from one another, jaw shifting means carried by said element, and means for automatically and substantially instantaneously locking the jaws against movement in one direction upon disconnection of the hook from the loop, including a movable member adjacent said loop and controlled as to movement by the hook.

40. 6. A lifter adapted for use in handling sheets and like articles and comprising in combination a horizontal supporting element having an up-standing loop for attachment to the hook of a crane or over head hoist, a pair of oppositely facing, horizontally elongated, complementary jaws pivoted to the opposite sides of the element so that they depend therefrom and are adapted to swing to and from one another, gear mechanism carried by said element for swinging the 45 jaws, and means for automatically and substantially instantaneously locking the gear mechanism against actuation in one direction upon detachment of the hook from the loop, including a substantially horizontal vertically movable member positioned adjacent the upper end of the 50 loop and adapted to be held in a raised position by the hook when the latter is in hooked relation with the loop and to be released for downward movement when the hook is detached from said loop.

60. 7. A lifter adapted for use in handling sheets and like articles and comprising in combination a horizontal supporting element having means on the central portion thereof for attachment to a crane or hoist, a pair of oppositely facing complementary jaws connected to the element so that they depend therefrom and are movable to and from one another, gear mechanism for conjointly moving the jaws, carried by said supporting element and including a gear segment with ratchet teeth thereon, and means for automatically and substantially instantaneously locking the gear mechanism against actuation in one direction upon disconnection of the attaching means from 65 said crane or hoist, including a dog shiftable into

and out of interlocked relation with said ratchet teeth.

8. A lifter adapted for use in handling sheets and like articles and comprising a pair of oppositely facing jaws mounted to move to and from one another, one of said jaws embodying a plurality of upper members and in addition a plurality of depending lower members connected pivotally at their upper ends to the upper members so that they may be swung laterally relatively to the latter into different angular positions in order to adjust the jaws for use with narrow or wide sheets, means operable conjointly to lock the lower members of said one jaw in their various adjusted positions with respect to 15 the upper members and also conjointly to release said lower members for adjustment purposes, including an elongated horizontal element extending longitudinally and substantially throughout the full length of said one jaw, and 20 means for conjointly shifting the jaws to and from one another.

9. A lifter adapted for use in handling sheets and like articles and comprising a pair of oppositely facing jaws mounted to move to and from 25 one another, one of said jaws embodying upper members and in addition aligned depending lower members connected pivotally at their upper ends to the upper members so that they may be swung laterally relatively to the latter into 30 different angular positions in order to adjust the jaws for use with narrow or wide sheets, means for releasably locking the lower members of said one jaw in their various adjusted positions with respect to the upper members and including 35 notched elements at the upper ends of the lower members and a dog equipped bar extending longitudinally of said one jaw and carried by the upper members so that it is longitudinally shiftable to bring the dogs thereof into and out of 40 interlocked relation with the notches of said elements, and means for conjointly shifting the jaws to and from one another.

10. A lifter adapted for use in handling sheets or other articles and comprising a pair of oppositely facing jaws mounted to move to and from one another, one of said jaws comprising a plurality of laterally spaced upper members and in addition a plurality of laterally spaced lower members having the upper ends thereof pivotally connected to the lower ends of the upper members so that they may be swung about said upper members into different angular positions with respect thereto in order to adjust the lifter for use with narrow or wide sheets, said lower 50 members having at the upper ends thereof sector shaped elements with arcuate series of teeth, means for conjointly locking the lower members of said one jaw in their various adjusted positions, comprising an elongated horizontal element extending longitudinally of said one jaw and carried by the upper members and provided with parts engageable with the teeth of the sector shaped elements, and means for conjointly shifting the jaws to and from one another.

11. A lifter adapted for use in handling sheets or other articles and comprising a pair of opposed jaws mounted to move to and from one another, one of said jaws embodying a plurality of laterally spaced upper members and in addition a plurality of laterally spaced lower members having the upper ends thereof pivotally connected to the lower ends of the upper members so that they may be swung sidewise relatively to said upper members into different angu- 75

lar positions for lifter adjusting purposes, said lower members having at the upper ends thereof sector shaped elements with arcuate series of teeth; means for conjointly locking the lower members of said one jaw in their various adjusted positions with respect to the upper members, consisting of an elongated horizontal element extending longitudinally of said one jaw and carried by the upper members so that it is

movable, and provided with parts adapted to engage the teeth of the sector shaped elements in response to movement of said horizontal element, and a latch carried by one of the upper members and adapted releasably to lock said horizontal element against movement; and means for conjointly shifting the jaws to and from one another.

ERARD J. SHAUGHNESSY.
